DUMP BODY AND TILT FRAME UNIT

Glenway Maxon, Jr., 1830 E. Kane Place,
Milwaukee, Wis. 53217

Filed Mar. 16, 1966, Ser. No. 1,490

Term of patent 14 years

(Cl. D14—3)

Fig. 1.

Fig. 2.

Fig. 3.

Fig. 4.

Fig. 5.

Fig. 6.

FIGURE 1 is a rear perspective view of a dump body and tilt frame unit embodying my new design;

FIGURE 2 is a front perspective view thereof;

FIGURE 3 is a rear elevational view thereof;

FIGURE 4 is a front elevational view thereof;

FIGURE 5 is a side elevational view thereof; and

FIGURE 6 is a top plan view.

The dominant features of my new design reside in those portions thereof illustrated by solid lines.

I claim:

The ornamental design for a dump body and tilt frame unit, as shown and described.
